UNITED STATES PATENT OFFICE.

HARRY C. MAIBOHM, OF SANDUSKY, OHIO.

DESIGN FOR A COMBINED RADIO LOUD SPEAKER AND LAMP SUPPORT.

Application filed June 25, 1925. Serial No. 13,888. Term of patent 3½ years.

To all whom it may concern:

Be it known that I, HARRY C. MAIBOHM, a citizen of the United States, residing at Sandusky, in the county of Erie and State of Ohio, have invented a new, original, and ornamental Design for Combined Radio Loud Speaker and Lamp Support, of which the following is a specification, reference being had to the accompanying drawing, forming part thereof.

The figure is a perspective view of a combined radio loud speaker and lamp support of my design.

I claim:

The ornamental design for a combined radio loud speaker and lamp support, as shown.

HARRY C. MAIBOHM.
